BILLFOLD

Louis A. Mueller, Springfield, Ohio, assignor to
 The Springfield Leather Products Company,
 Springfield, Ohio, a corporation of Ohio

Application January 22, 1938, Serial No. 186,346

2 Claims. (Cl. 150—38)

This invention relates to billfolds, particularly to that class of billfolds which have at least two inner spaced-apart pockets with a panel or slip connection bridging the space between the pockets.

In billfolds of this character it is usual to provide a flexible panel or slip connection to bridge the space between the inner pockets, the ends of which are inserted in the pockets and at least one end of which is slidably connected in the pocket in which it is inserted to permit the parts to slide or slip relatively to each other when the billfold is folded.

The object of the present invention is to provide means for connecting at least one end of a slip connection in the pocket in which it is inserted which will be simple in construction and effective in operation.

A further and more specific object is to provide an attachment between the slip connection and one of the walls of a pocket in which it is inserted which will be of a character to prevent the parts from becoming disconnected and at the same time provide for the necessary slippage.

In the accompanying drawings:

Fig. 1 is an elevation of the inner side of a billfold embodying the improvements partly broken away to better illustrate some of the details.

Fig. 2 is a view of part of a billfold before the parts have been folded together to illustrate the manner of assembly.

Fig. 3 is a section on the line 3—3 of Fig. 1.

Fig. 4 is a view of the blank from which the billfold is formed with the upper edges of two of the walls of one of the pockets shown stitched together and the slip connection shown connected to one of said walls.

Fig. 5 is a view similar to Fig. 4 but showing the parts in partly folded position.

Fig. 6 is a perspective view of the billfold in partly folded position.

Fig. 7 is a view of a portion of the billfold showing a modification with some of the parts broken away.

Fig. 8 is a section on the line 8—8 of Fig. 7.

Fig. 9 is a view of a portion of a billfold with some of the parts broken away showing a further modification.

Fig. 10 is a section on the line 10—10 of Fig. 9.

Referring first to Figs. 1 to 6, inclusive, of the drawings, 1 represents a flexible outer wall, the upper edge of which preferably has a small flap 1' which is folded over and attached to the wall proper to give a good finish. Referring first to

that end of the billfold having the pocket in which the slip connection is slidably mounted, 2 represents one of the flexible inner wall members forming a pocket, which wall 2 is integrally attached to the end of the outer wall 1. A second flexible inner wall member 3 is adapted to be secured to the wall member 2 by means of a flap 4 on the upper edge of the wall member 2 which is stitched to the upper edge of the wall member 3 by a line of stitching 5. These two inner wall members 2 and 3 are also stitched in the final assembly of the device along their lower edges by a line of stitching 6.

The flexible panel or slip connection which bridges the space between the two opposite inner pockets is indicated at 7, one end of which is inserted in the pocket formed by the two inner wall members 2 and 3. In order to secure the end of the slip connection in this pocket in a

way which will permit it to slide but at the same time hold it securely in position, the wall member 3 in the present instance is slit vertically with two parallel slits to form a tongue 8, the free end of which terminates at the upper edge of the wall, and the slip connection in the pres-

ent instance is slit longitudinally by two parallel slits to provide an elongated loop 9. In assem-

bling the structure, the tongue 8 of the wall 3 is inserted through the loop 9 of the slip con-

nection before the walls 2 and 3 are secured to- 30

gether along their upper edges. The upper edge of the wall 3 is then laid upon the flap 4 and stitched thereto by the row of stitching 5 be-

fore referred to, the upper edge of the slip con-

nection being bent back so that the stitches 35

will not pass through the slip connection, the edge of the slip connection being shown partly bent back in Figs. 2 and 4, it being understood,

however, that it will be bent back far enough so that the stitching 5 can be made without pass-

ing through the slip connection. The stitches 5, 40

however, do pass through the tongue 8 so as

to form in effect two interlocking loops between

the wall 3 and the slip connection which will

effectively prevent the slip connection and the

wall 3 from becoming detached, but due to the

fact that the longitudinal slits in the slip con-

nection are of considerably greater length than

the width of the tongue 8 to provide an elongated

loop, the tongue 8 may readily slide back and

forth along the loop 9 so as to provide for the

necessary slippage of the connection 7 when the

billfold is folded. After the flap 4 has been

stitched to the upper edge of the wall 3 includ-

ing the tongue 8, the wall 3 and slip connection

55

- are folded upon the wall 2 as shown in Fig. 5 and the two walls 2 and 3 stitched together along their lower edges by the stitching 6 before referred to. It will be understood that when 5 the stitching 5 is made the wall 3 and slip connection will be in the position shown in Fig. 4 so that the edge of the slip connection may be readily bent back to permit the stitching to be made, after which the wall 3 and slip connection 10 are folded over upon the wall 2. The pocket thus formed by the walls 2 and 3 together with the slip connection which has now been slidably secured in the pocket is then folded upon the outer wall 1 as shown in Fig. 1.
- 15 The slip connection is then inserted beneath an inner wall 10, one edge of which is integrally fastened to the outer wall 1 and the upper edge of which has a flap 11 which in the present case is stitched to the panel 7 by stitches 11' so as to 20 firmly secure that end of the panel in position. Any other means of securing the panel in the pocket at the right-hand end of the bill-fold, however, may be employed without departing from the spirit of this invention.
- 25 After the walls 2 and 3 and the slip connection have been folded over upon the outer wall 1 in the manner shown in Fig. 1, they are secured to the outer wall by a flap 12 integrally secured to the lower edge of the outer wall and having a 30 reduced portion 12' which is slipped through longitudinal slits 13 in the wall 2, these slits forming a loop 14. This flap 12 is slit to form a small tongue 15 which after the part 12' has been inserted through the loop 14, is inserted through a 35 slit 16 in the loop 14 to secure the parts 12' in position. The flap 12, its extension 12', and the tongue 15 are all attached by gluing or otherwise to the wall loop 14.

The other end of the billfold also has a flap 40 17 which is inserted through slits 18 in the wall 10 and is provided with slits to form a small tongue 19 which is inserted through a slit 20 to hold the parts in position.

By this construction it will be seen that the 45 slip connection 7 and the wall member 3 are firmly secured against displacement with relation to each other excepting that a sliding movement is allowed between the same, the fact that the tongue is stitched to the flap 4 of the wall 2 50 forming an interlocking connection eliminating any chance of the tongue of the wall and the loop of the slip connection from becoming disconnected.

In Figs. 7 and 8 there is shown a modification 55 in the form of the slidable connection between the panel or slip connection and the wall of the pocket in which it is inserted, the pocket wall being also changed somewhat from that shown in the preceding figures. In these modified views, 60 21 represents a portion of the outer wall and 22 the panel or slip connection. The inner wall member with which the panel is slidably connected is indicated at 23, this inner wall member being in the present case in the nature of a comparatively short wall as to height which is not 65 stitched at the bottom as in the preceding construction. This inner wall member 23 is provided with two parallel vertical slits 24 to form a loop 25 and the slip connection or panel 22 is provided 70 with longitudinal slits 26 to form a tongue 27 which is slipped through the loop of the wall. The tongue 27 after it has been inserted through the loop of the wall is stitched to the panel or slip connection by a row of stitching 28. The

principal difference in construction between this modified view and the billfold described in Figs. 1 to 6, inclusive, is that the loop is formed on the pocket wall and the tongue on the slip connection or panel; also, that which has been termed 5 the pocket wall 23 is a comparatively short wall as to height instead of a wall which extends to the bottom of the billfold and is stitched to the outer wall as in the previous construction.

In Figs. 9 and 10 there is shown a further 10 modification, this arrangement being more particularly to show that the inner wall, indicated at 29, is a comparatively short wall such as the one shown in Figs. 7 and 8. In this arrangement, however, the tongue and loop connection between 15 the inner wall and the panel or slip connection indicated at 30 is the same as illustrated in Figs. 1 to 6, inclusive; that is, the tongue, indicated at 31 is formed on the wall 29 and the loop indicated at 32 is formed in the slip connection, the 20 tongue and loop being formed by arranging the respective parts as described in the construction illustrated in Figs. 1 to 6. A portion of the outer wall is indicated at 33. In this case the inner wall member 29 is stitched by the row of 25 stitching 34 to its companion wall member 35, such as illustrated in Figs. 1 to 6.

Having thus described my invention, I claim:

1. In a receptacle such as a billfold, an outer 30 flexible wall, an inner flexible wall member co-operating with said outer wall to provide a compartment extending longitudinally of the billfold and opening along the upper longitudinal edge thereof, an inner pocket wall member, an extension on the upper edge of said pocket wall member, said pocket wall member lying on one side of said inner wall member and said extension on the opposite side thereof when the receptacle is in assembled position, said extension and inner wall member having interengaging parts 35 consisting of an elongated loop on one of said members formed by parallel spaced slits and a tongue on the other member formed by parallel spaced slits arranged at right-angles to the other slits and adapted to be received in said loop to slidably 40 connect said parts together, and means to secure the free end of said tongue to the wall member on which it is formed to form in effect two interlocking loops between said extension and inner wall member. 50

2. In a receptacle such as a billfold, an outer flexible wall, an inner flexible wall member co-operating with said outer wall to provide a compartment extending longitudinally of the billfold and opening along the upper longitudinal edge 55 thereof, an inner pocket wall member, an extension on the upper edge of said pocket wall member, said pocket wall member lying on one side of said inner wall member and said extension on the opposite side thereof when the receptacle is in assembled position, said extension and inner wall member having interengaging parts 60 consisting of an elongated loop formed on said inner wall member by parallel spaced slits and a tongue formed on said extension by parallel spaced slits 65 projecting at right angles to the slits of said inner wall member, said tongue being inserted through said loop to slidably connect said members together, and means to secure the free end of said tongue to its associated wall member to 70 form in effect two interlocking loops between said panel and inner member.
